[57] CLAIM

The ornamental design for a fan enclosure, as shown and described.

DESCRIPTION

FIG. 1 is a perspective view taken from the top, front and left side of a fan enclosure showing my new design;

FIG. 2 is a front elevational view thereof;

FIG. 3 is a rear elevational view thereof;

FIG. 4 is a left side elevational view thereof;

FIG. 5 is a bottom plan view thereof;

FIG. 6 is a right side elevational view thereof; and

FIG. 7 is a top plan view thereof.

The fragmentary broken line representation of a computer terminal in FIG. 1 is for purposes of illustration only.
